UNITED STATES PATENT OFFICE.

WILLIAM A. TURNER, OF SAN FRANCISCO, CALIFORNIA.

STREET OR STATION INDICATOR AND CARD-DISPLAYING DEVICE.

SPECIFICATION forming part of Letters Patent No. 394,741, dated December 18, 1888.

Application filed April 24, 1888. Serial No. 271,733. (No model.)

To all whom it may concern:

Be it known that I, WILLIAM A. TURNER, of San Francisco, San Francisco county, State of California, have invented an Improvement 5 in a Card Display and Indicator; and I hereby declare the following to be a full, clear, and exact description of the same.

My invention relates to a novel street and station indicator and card-displaying device, 10 and its object is to construct an appliance which shall utilize all the space in the indicator-box for the successive display of cards or signs bearing names or other matter.

My invention consists, essentially, of a box 15 or case whose front, with the exception of a small space at the upper left-hand corner, is transparent, and which is filled or nearly filled by two sets of advertising cards or plates, together with mechanism by which 20 one set is forced toward the front and the other toward the rear of the box, and in combination with this of pulling-grips by which the front plate is pulled to one end and the rear plate is pulled to the opposite end, the 25 two being simultaneously drawn in opposite directions together, with the mechanism for operating the same, all of which will be more fully described by reference to the accompanying drawings, in which—

30 Figure 1 is a perspective view of my device. Fig. 2 is a bottom view, the bottom plate being removed. Fig. 3 is a vertical section of the bottom part of the box, taken through the line $y y$ of Fig. 2.

35 A is the box containing the plates B, which are of such relative size that when two plates are placed end to end their joint length is a little less than the internal length of the box, and the width of each plate is a little less 40 than the internal width of the box. The internal depth of the box A is equal to the thickness of one of the sets of plates or cards plus the thickness of one and one-half plate, so that the top plate of either set may pass readily upon the other set. The whole of the two 45 front plates which stand side by side are exposed by the transparent front of the case, except the upper part of one side, which is covered by an opaque plate, S, so that as the 50 movable card or plate slides across the front of the box the name of the street which is

imprinted upon its upper edge will be concealed by this opaque plate.

The advertising plates or cards are arranged in two sets, B and B', as above described. 55 The set B receives a constant pressure toward the rear of the box by the springs C and C², and is maintained in a perpendicular position by the springs D D². The set of plates B' receives a constant tendency toward the 60 front of the box by means of the springs C², and is maintained in a perpendicular position by the springs D², corresponding with the springs D of the first set of plates, as described. By this means a small space is left 65 behind one set of plates and in front of the other set, which is sufficient to allow one card from each set to be moved past the other set simultaneously and in opposite directions. In order to guide these plates in their trans- 70 verse or side movements and to prevent the adjacent edges from interfering as they pass each other, short transverse rails a are fixed in the bottom of the box, there being a sufficient distance between their ends and the 75 sides of the box to allow the plates to slide from end to end when they are transferred by the pulling-grips. The lower edges of the cards or plates are grooved or notched, so as to fit and slide upon the guides a when the 80 notches arrive opposite the ends of the rails.

At the bottom of the box, and extending longitudinally from end to end, is a groove or slot, in which slides the front pulling-grip, E. This pulling-grip is designed to move the 85 cards, and at the same time to occupy the least possible space. It has a flexible arm, F, and a hook, G, this hook dropping beyond the edge of the card or plate to be moved, so that when the grip is pulled forward it draws 90 a card, causing it to pass from one end to the other of the box and beneath the holding-springs C and D, above described.

Parallel with and behind the first groove in the bottom of the box is a second longitudinal groove or slot, in which slides a second pulling-grip, E', constructed like the first, but moving in the opposite direction and acting upon the rear card or plate of the other set. For the purpose of operating the indicator 100 cords I and J are attached to the pulling-grip. For the convenient attachment of

these cords I have in the present case shown two projecting pins. These cords pass around pulleys L and M and are attached to said pulleys in such a manner that when one of the 5 pulling-grips is moved the other receives a corresponding motion. Each pulling-grip has a constant tendency toward one end of the box, this being caused by the tension of a spring, which in the present case I have shown as a 10 coil-spring, N, which may operate upon one of the pulleys. A cord, P, for operating the indicator, is attached at some convenient point. In the present case I have shown it as attached to the pulley L. In the length of the 15 cord or chain I have shown a stout spring, O, which, if an overpull be given to the cord or chain, will yield, so as to save the apparatus from injury.

The rigidity of the box may be increased, if 20 desired, by means of a narrow transverse partition or stay between the ends of the two sets of cards.

When the device is in operation, the advertising-space of two cards will be exposed to 25 view, while the name of only one street or station will appear, and thus any number of streets, stations, advertising-cards, or other devices may be exposed, and the whole apparatus will occupy but little more space than 30 is sufficient to contain the cards themselves, while the operating mechanism is reduced to the least possible amount. When the cord P is pulled, the grips E E' will seize the front and rear plates of the two series, respectively, 35 and draw them in opposite directions and to opposite ends of the box. As these plates pass beneath the springs C and C', they are forced transversely across the indicator-box, one set from the rear toward the front and 40 the other set from the front toward the rear. When the pull upon the cord is released, the grips are returned to their original position by the action of the spring N, above described, and are thus in a position to move the succeeding 45 pairs of plates in the same manner.

R R are latches fixed to the top or bottom of the box, so as to move up and down in the plane in which the plates stand.

When the plates are moved longitudinally 50 along the front and rear of the box, they depress the latches R, and when the plates have reached the end of their longitudinal course they are pushed transversely by the springs C and D and pass beyond the latches R, 55 which latches then spring out in front of the plates and prevent their return into the spaces at the front and back, which must be kept open for the succeeding plates to slide in.

Having thus described my invention, what I claim as new, and desire to secure by Letters 60 Patent, is—

1. In a street or station indicator, a box or case having two sets of cards or plates nearly filling it, springs by which one set of cards or plates are forced to the front and the other 65 set to the rear, and oppositely-moving grips for moving the cards lengthwise of the box, substantially as herein described.

2. The box containing two sets of cards or plates and the grips by which the cards or 70 plates at the front and rear are moved in opposite directions, in combination with springs for moving one set of plates toward the front and the other set toward the rear, the pulleys, and connecting-cords whereby the two grips 75 are made to operate simultaneously, one of said pulleys having a returning-spring connected with it, substantially as herein described.

3. The case with the cards or plates, springs 80 for moving said plates front and rear, and grips and connections for moving the plates lengthwise of the box, in combination with the latches R, which fall in front of the cards and prevent their falling into the spaces 85 reserved for the travel of succeeding cards, substantially as herein described.

4. The combination, with the case, the two sets of cards or plates, and the springs bearing against the plates to force one set toward 90 the front and the other set toward the rear, of the grip or device for moving the cards or plates, consisting of the flexible arm, the beveled head or hook, and the body with points for the attachment of the actuating-cords, 95 substantially as herein described.

5. The two sets of cards or plates, the springs for forcing one set toward the front and the other set toward the rear, the grips and connections for moving the cards or plates lengthwise, and the box or case having a transparent 100 front exposing both cards which stand side by side, in combination with an opaque plate covering the upper edge of one of the cards, so as to conceal the name of the street or station just passed when the card containing it has been moved beneath this plate, substantially as herein described.

In witness whereof I have hereunto set my hand.

WILLIAM A. TURNER.
